Hoover Company, North Canton, Ohio

Application February 5, 1940, Serial No. 317,377

18 Claims. (Cl. 62—119.5)

This invention relates to the art of refrigeration and more particularly to a novel absorption refrigerating system involving unique control and regulating features.

This invention particularly relates to three-fluid absorption refrigerating systems of the type in which a circulating motor is hermetically sealed within the system in order to circulate the fluids therein. Motors of this type must be lubricated. However, considerable difficulty may arise in handling and installing the system due to the fact that under such circumstances the lubricant in the motor shell may be displaced by foreign material such as absorption solution and once displaced it will be very difficult to return the lubricant to its normal environment without materially reconstructing the apparatus. In order to obviate this difficulty, it is an object of the present invention to lubricate the motor with a lubricating material which is not fluid at normal temperatures and which will flow at the temperature maintained by the heat generated by the motor winding in order to perform its lubricating function efficiently. The lubricant has another effect, namely, it imposes sufficient drag upon the rotating portions of the motor to prevent the same from operating until the lubricant has been liquefied as by the application of heat. This factor, however, is not disadvantageous by reason of the fact that there is an appreciable lapse of time between energization of the boiler heater and discharge of liquid refrigerant into the evaporator and circulation of inert gas and absorption solution during this period of time is not desirable. Therefore, the delay in action of the motor with respect to the actuation of the refrigeration control mechanism and energization of the boiler heater may advantageously be utilized to improve the operating characteristics of the system.

With some lubricants, such as those having a high paraffin content, the period required to liquefy the same by the heat generated by the very small current flowing through the windings of motors is excessive, wherefore it is an object of the present invention to provide an additional heating element so designed and arranged that the motor will come into operation substantially simultaneously with supply of liquid refrigerant to the evaporator and will be de-energized automatically after liquefaction or softening of the lubricating material in which the motor is submerged.

It is a further object of the invention to provide an apparatus of the above character in which the motor is immersed in a lubricant which will con-

5 geal or become non-fluid at ordinary temperatures and which includes a heating apparatus constructed and arranged to maintain the lubricant in the liquid or fluid state substantially continuously after initial installation of the apparatus.

It is a still further object of the present invention to provide an absorption refrigerating system which includes a lubricated circulator provided with a lubricant heater for softening the lubricant, which heater is de-energized in response to a temperature change in a particular portion of the refrigerating system.

Other objects and advantages of the invention will become apparent as the description proceeds when taken in connection with the accompanying drawing, in which:

20 Figure 1 is a diagrammatic representation of a three-fluid absorption refrigerating system embodying the present invention;

Figure 2 is a partial sectional elevational view drawn on an enlarged scale of the motor circulator unit of the system;

25 Figure 3 is a schematic wiring diagram of a modified form of control circuit.

Referring now to the drawing in detail and first to Figure 1 thereof, there is illustrated a three-fluid absorption refrigerating system comprising a boiler B, an analyzer D, an air-cooled rectifier R, a tubular air-cooled condenser C, an evaporator E, a gas heat exchanger G, a tubular inclined air-cooled absorber A, a liquid heat exchanger L, a solution reservoir S, and a circulating fan F which is driven by an electrical motor M. These elements are suitably connected by various conduits to form a plurality of gas and liquid circuits constituting a complete refrigerating system to which reference will be made in more detail hereinafter.

30 40 The above described refrigerating system will be charged with a suitable absorbent, such as water, a suitable refrigerant, such as ammonia, and an inert pressure equalizing medium, preferably a dense inert gas like nitrogen.

45 The boiler B is arranged to be heated by a gas burner H which will be described in more detail hereinafter. The application of heat to the boiler B generates refrigerant vapor from the solution therein contained. The vapors so generated pass upwardly through the analyzer D in counterflow to the strong solution flowing downwardly therethrough. After traversing the analyzer D the vapor is conveyed from the upper portion thereof to the upper portion of the con-

denser C by means of a conduit 11 which includes the rectifier R.

The lean solution formed in the boiler by the generation of refrigerant vapor therefrom is conveyed from the boiler to the solution reservoir S by way of the conduit 12, the liquid heat exchanger L, and a finned looped conduit 13 which also serves as a solution precooler.

The solution reservoir S is vented by means of a conduit 14 which connects to the suction conduit 15 of the circulating fan F. The conduit 15 extends between the suction side of the fan F and the upper portion of the absorber A.

The lean solution is conveyed from the reservoir S to the conduit 15 adjacent its point of connection with the absorber A by means of a gas lift pumping conduit 16. Pumping gas is supplied to the conduit 16 by means of a conduit 17 which is connected between the discharge conduit 18 of the circulating fan F and the gas lift pump 16 below the liquid level normally prevailing therein and in the solution reservoir S.

The lean solution flows downwardly through the absorber A in counterflow relationship to a rich mixture of inert gas and refrigerant vapor which is supplied to the bottom portion of the absorber from the evaporator in a manner to be described hereinafter.

In its traverse through the absorber the lean solution absorbs refrigerant vapor from the gas mixture flowing therethrough and the resulting heat of absorption is rejected by the cooling fins to cooling air flowing over the exterior walls of the absorber vessel.

The strong solution thus formed in the absorber is conveyed therefrom to the upper portion of the analyzer D by way of the conduit 19, the liquid heat exchanger L, and a conduit 20, thus completing the absorption solution circuit.

Lean inert gas is formed in the absorber A by the absorption of refrigerant vapor and is then conveyed from the upper portion of the absorber to the suction side of the circulating fan F by means of the conduit 15. The inert gas is placed under pressure in the fan F and is then conveyed therefrom to the lower portion of the evaporator E by way of the conduit 18, the outer path of the gas heat exchanger G and an evaporator gas supply conduit 22.

The refrigerant vapor which is supplied to the condenser C is liquefied therein by heat exchange relationship with atmospheric air and is then conveyed therefrom to the bottom portion of the evaporator E by way of the conduit 23 and a conduit 24 which includes a downwardly extending U-shaped looped portion which is designed to carry a liquid seal and a pressure balancing column of the liquid refrigerant. The conduits 23 and 24 are vented by means of a conduit 25 to the rich gas side of the gas heat exchanger G. As a result of this construction the pressure prevailing in the condenser and the condenser side of the conduit 24 is that prevailing on the discharge side of the evaporator whereas the pressure prevailing on the discharge side of the conduit 24 is that prevailing at the inlet to the evaporator. This pressure difference is compensated by a pressure balancing liquid column which is supported in the condenser side of the conduit 24.

The evaporator E may be of any desired type of construction. However, as diagrammatically illustrated herein, it is of the type in which the high velocity gas stream flowing through the evaporator serves to sweep or drag liquid refrigerant

upwardly therethrough as it is evaporating to produce refrigeration. A preferred construction of this type evaporator is disclosed and claimed in the co-pending application of Curtis C. Coons and William H. Kitto, Serial No. 220,189, filed July 20th, 1938. An anti-blocking and overflow drain 27 is connected between the upper portion of the bottom conduit in the evaporator E and the strong solution return conduit 19.

10 The liquid refrigerant supplied to the bottom portion of the evaporator E meets a high velocity gas stream flowing upwardly therethrough with the result that the liquid refrigerant is propelled upwardly through the evaporator as it is evaporating into the gas stream to produce useful refrigeration.

15 The top portion of the evaporator is provided with a large diameter finned box-cooling conduit 28 into which both the liquid and gas discharge. The gas flows at a slow rate through this conduit, hence the same is inclined rearwardly in order to permit liquid to flow by gravity. The resulting rich gas and unevaporated material in the evaporator is conveyed from the conduit 28 into the rich gas side of the gas heat exchanger G by means of a conduit 29. After traversing the rich gas side of the gas heat exchanger the rich gas and unevaporated material is drained therefrom into the bottom portion of the absorber A by means of the conduit 30. Thus, the conduit 30 serves as a rich gas return conduit and as an evaporator drain. The rich gas then flows upwardly through the absorber A in counterflow relationship with the lean solution flowing downwardly therethrough in the manner heretofore described.

20 It will be noted that with the construction thus provided evaporator drainage is conveyed to the conduit 19 in a manner such that it cannot reach the circulating fan and the fan is so connected to the absorber that lean solution cannot be conveyed thereto from the lean solution supply lines. This is of considerable importance in preventing absorbing solution from finding its way to the motor shell, as will be explained in more detail hereinafter.

25 Referring now to Figures 1 and 2, it is apparent that the fan casing F carries a sealed motor shell 35 depending therefrom. The motor M consists of a rotating element 36 which is mounted within the shell and a stationary field winding or stator structure 37 which is mounted on the outside of the shell whereby the magnetic circuit for the induction rotor 36 must pass through the shell 35. The rotor is supported on suitable bearing assemblies indicated generally at 38 and 39 within the shell 35. The motor shaft 40 passes through the bearings 38 and carries a suitable fan within the fan housing 41 in a conventional manner.

30 The depending motor shell 35 is filled with a suitable lubricant up to the level of the line indicated generally at 44; that is, the rotor is completely submerged and part of the bearing 38 is submerged in the lubricant.

35 One such lubricant is paraffin and it is obtainable in a long range of melting points and specific gravity. By selecting paraffin of the proper melting point or by mixing it with other lubricants, almost any melting point desired can be obtained. This lubricant has the characteristic that it is non-fluid at ordinary room temperatures but will become fluid when heated above that temperature in order to lubricate the bear-

ings to permit the motor to rotate. In its non-fluid state the drag of this lubricant is sufficient to stall the rotor of the motor.

In this connection it should be emphasized that this motor is very small and develops only sufficient power to circulate the inert gas with a few inches of water pressure differential, hence the lubricant drag is easily sufficient to stall the same.

In order to shorten the time required for the lubricant to be rendered fluid by heat, a suitable electrical heating element 45 is positioned about the motor shell 35 and at the lower end thereof below the stator 37 of the electrical motor. The heater is encased in a suitable refractory channel-shaped element 46 which protects the stator windings from the heat. A housing 47 of insulating material is suitably attached to the bottom portion of the motor shell 35 beneath the heater 45 and is provided with a switching enclosure or chamber 48. An electrical switch indicated generally at 49 is encased within the chamber 48. A bracket 50 is attached to the bottom portion of the shell 35 and carries a thermostatic strip or disc 51, as may be desired, directly above the switch 49. The disc 51 is provided with an actuating button 52 which may be made of a composition insulating material and is positioned to strike the movable element 53 of the switch 49 to actuate the same.

As was mentioned previously a heater H is provided for the boiler B. Gas is supplied to the heater H from a suitable source of supply through a conduit 55 which includes a solenoid valve V. A small by-pass 56 is provided around the valve V in order to maintain a small ignition flame on the heater H. Also included in the conduit 55 adjacent the burner is a suitable thermostatic safety cut-off device 57 which is arranged to discontinue supply of fuel to the burner completely upon failure of flame thereupon, as for example in case the small igniting or pilot flame is extinguished by a draft or the like.

The apparatus is controlled by means of a suitable thermostatic switching mechanism indicated generally at 60 and provided with a capillary conduit 61 which connects to a fluid containing bulb 62 positioned to be influenced by temperature changes at or adjacent the evaporator E. The exact construction of the thermostatic switching mechanism 60 is conventional and need not be disclosed in detail herein. Power is supplied to the apparatus from a pair of electrical conductors 63 and 64. The conductor 63 connects directly to the switching mechanism 60. An electrical conductor 65 is connected to the switching mechanism 60 and to the windings 66 of the stator 37 of the motor M. The other side of the winding 66 connects directly to the electrical conductor 64. The heating element 45 is connected to the conductor 65 by means of a conductor 67. The other side of the heating element 45 is connected to the switch 49 by means of a conductor 68 and the switch 49 then connects to the conductor 64 by means of a conductor 69. The solenoid valve V is connected to the conductors 64 and 65 by means of the conductors 71 and 72, respectively.

The operation of the device, except insofar as the same has already been disclosed in connection with the construction of the refrigerating apparatus per se, is as follows: Assuming a demand for refrigeration, the thermostatic switch 60 will complete the electrical circuit between the conductors 63 and 65. This will then directly

10 energize the windings 66 of the motor and the solenoid valve V. Upon energization of these elements the flame will be turned up upon the burner H for the purpose of heating the boiler 5 and if the motor M has cooled sufficiently to cause congelation of the lubricant contained in the shell 35, the thermostat 51 will have flexed upwardly to the position shown in Figure 2 to permit the movable element 53 of the switch 49 to move to closed circuit position, thereby energizing the heater 45. After a lapse of a short period of time the heat of the current flowing in the winding 66 and the heat of the heating element 45 will be sufficient to render the lubricant fluid and thereby to eliminate the braking action thereof upon the motor. The motor now comes into operation to circulate the inert gas and absorption solution through their responsive circuits. The period required to heat the lubricant sufficiently to render the same fluid is such that the motor will come into operation at substantially the time liquid refrigerant begins to discharge through the conduit 24 into the evaporator E.

15 25 Immediately the motor lubricant becomes fluid the temperature thereof is at a value sufficient to actuate the thermostat 51 which causes the same to flex downwardly, as viewed in Figure 2, to shift the movable element 53 of the switch 49 to open circuit position thereby de-energizing the heater 45. The heat supplied from the motor itself is sufficient to maintain the lubricant in a fluid state once the same has been initially conditioned by the heating element 45. Hence, a 20 30 differential heating rate is applied to the lubricant, a high rate for melting and a low rate to maintain the lubricant in a fluid state.

35 The apparatus remains in this condition so long as the temperature of the evaporator has not been lowered to the value for which the control mechanism is set. Once the evaporator temperature lowers to the value for which the control has been set, the circuit between the conductors 63 and 65 is broken by the switching 40 mechanism 60, the valve V closes thereby leaving only the small pilot or ignition flame upon the burner H which is maintained by gas flowing through the conduit 56 and the circulating motor is de-energized. If the motor remains de-energized for an appreciable period of time, and it usually will remain de-energized for such a period of time, the motor will cool sufficiently to cause congelation of the lubricant within the shell 35 and the thermostat 51 will flex upwardly to the 45 50 55 position shown in Figure 2, to close the circuit between the conductors 68 and 69, thereby conditioning the heater 45 to be energized upon closure of the circuit between the conductors 63 and 65 by the control mechanism 60.

60 65 As at present advised the illustrated construction is the preferred arrangement, however, the thermostatic cut-out for the lubricant heater may be arranged to de-energize the heater in response to a change in the condition of another portion of the system induced by energization of the system. For example, the thermostatic cut-out for the lubricant heater could be arranged to respond to the temperature of some portion of the pipe 11. This pipe is heated by hot vapor 70 75 enroute to the condenser. There is a time lag between initiation of full flame operation of the burner and heating of this pipe which will allow sufficient heating of the lubricant to render the same fluid and will produce the desired lag in operation of the motor with respect to the burner.

The present invention provides a very advantageous arrangement in that loss of lubricant from the motor shell and/or displacement thereof by liquid refrigerant or absorption solution during transit of the refrigerating system and installation thereof is absolutely prevented by reason of the fact that the lubricant is in a non-fluid state prior to operation thereof. This is of considerable importance as it is impossible to insure that the apparatus will be maintained in upright position during handling and shipment.

The lubricant also has an advantageous effect with respect to the operation of the refrigerating system and control thereof in that the arrangement herein provided automatically prevents circulation of absorption solution and inert gas until the boiler has been fully heated and liquid refrigerant has been supplied to the evaporator at which time the system is conditioned to go into complete operation. Considerable loss is entailed if the inert gas is circulated during the period of time required to bring the liquid in the boiler up to the boiling temperature because this circulates absorption solution thereby continuously removing the heated liquid from the boiler and cooling the same in the absorber and it also circulates inert gas warmed by contact with the solution in the absorber through the evaporator thus adding to the net refrigerating load when liquid refrigerant is eventually supplied to the evaporator. The present arrangement obviates these difficulties.

In Figure 3 there is diagrammatically illustrated a modified form of the invention. This form of the invention is designed and intended to be utilized with a refrigerating system identical with that illustrated and described in connection with Figures 1 and 2, the only differences being in the arrangement of the wiring. Therefore, only a schematic wiring diagram has been illustrated. Certain portions of the apparatus illustrated in Figure 3 are identical with portions illustrated and described in connection with Figures 1 and 2 and are therefore given the same reference characters primed.

In the form of the invention illustrated in Figure 3, electrical energy is supplied to the apparatus by the conductors 80 and 81. The conductor 80 connects directly to one side of the winding 66' of the circulating motor and it is connected to the valve V' and heater 46' by the conductors 82 and 83, respectively. The opposite sides of the winding 66' is connected to the valve V' by the conductor 84 which in turn is connected to the control 60' by a conductor 85. The heater 46' is also connected to the thermostatic switch 49' by means of a conductor 86. The switch 49' is then connected to the control 60' and to the supply line 81 by means of a conductor 87.

As may readily be seen from an inspection of Figure 3, in this form of the invention the windings 66' and the valve V' are directly under the control of the thermostatic switching mechanism 60' but the heater 46' and associated thermostatic switch is connected in parallel in such fashion that the same does not come within the control of the control mechanism 60', wherefore the heater 46' will be energized whenever the temperature of the lubricant within the motor housing drops below a predetermined point, provided electrical energy is supplied, in order to maintain the lubricant in a fluid condition and will be de-energized by the thermostat 51' whenever the temperature of the lubricant is above 70

its non-fluid point in order that the motor may be in condition for starting operation at any time.

This form of the invention does not delay the action of the motor with respect to the action of the boiler in the manner characteristic to the form of the invention described in connection with Figures 1 and 2. In this form of the invention it is intended that the by-pass conduit 10 56' will be constructed to maintain sufficient flame on the heater H to keep the boiler B at substantially the vaporization point at all times so that vapor will be evolved substantially immediately the valve V' is opened by the control mechanism to place a full flame on the burner. Consequently under these conditions it is not necessary to delay the action of the circulating motor with respect to the action of the heater.

This form of the invention will also be utilized 20 with a normally non-fluid lubricant such as that disclosed in connection with Figures 1 and 2 in order to prevent loss of lubricant from the motor housing during shipment and installation. However, once installed, the lubricant is maintained 25 in fluid condition substantially continuously. This form of the invention is particularly applicable for use in refrigerating units which are called upon to meet sudden heavy demands and also for units which are designed to be used in 30 unusually cold climates where the delay caused by continual softening or melting of the lubricant would be objectionable and also the cooling of the boiler in the off-cycle period with a mere pilot flame on the burner H would be objectionable.

In accordance with the invention herein disclosed there is provided an absorption refrigerating apparatus in which the motor is immersed 40 in a solid lubricant which is rendered fluid after installation of the apparatus and is either maintained continuously in a fluid condition thereafter or is periodically reheated to render the lubricant fluid whenever the apparatus is called upon to produce refrigeration.

Though the invention has been illustrated and described herein in considerable detail, various alterations and changes may be made in the proportion, construction and arrangement of parts without departing from the spirit of the invention or the scope of the appended claims.

I claim:

1. Absorption refrigerating apparatus of the type having a hermetically sealed fluid circulator therein, an electrically driven element for 55 said fluid circulator also sealed within the apparatus, a lubricant for said electrically driven element sealed in said apparatus, said lubricant being of the type which is non-fluid at atmospheric temperatures, an electrical heater for said lubricant, and means for opening the energizing circuit of said electrical heater when the temperature of said lubricant is sufficiently high to maintain the same in the fluid state.

2. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a circulating device included in said inert gas circuit, a gas lift circulator in said solution circuit, means for conveying pumping gas from said inert gas circuit to said gas lift circulator, a motor for driving said circulating device having its 70 75 rotating element sealed within the inert gas cir-

cult, a lubricant submerging said rotating element, said lubricant being of the type which congeals at atmospheric temperatures, a heater for said lubricant, and means for de-energizing said heater when the temperature of said lubricant rises sufficiently to liquefy the same.

3. Absorption refrigerating apparatus comprising an inert gas circuit including an evaporator and an absorber, a solution circuit including a boiler and said absorber, means for liquefying refrigerant vapor produced in said boiler and for supplying the liquid to said evaporator, a circulating device included in said inert gas circuit, a gas lift circulator in said solution circuit, means for conveying pumping gas from said inert gas circuit to said gas lift circulator, a motor for driving said circulating device having its rotating element sealed within the inert gas circuit, a lubricant at least partially submerging said rotating element, said lubricant being of the type which congeals at atmospheric temperatures, a heater for said boiler, a heater for said lubricant, refrigeration demand responsive means arranged to energize said heaters and said motor in response to refrigeration demand, and means for de-energizing said lubricant heater independently of said refrigeration demand responsive means when the temperature of the lubricant has risen sufficiently to liquefy the same.

4. In an absorption refrigerating system of the three-fluid type, a motor driven circulator for circulating fluids in the system, said motor including a rotating part sealed within the system and at least partially immersed in a lubricant, a heating element for said lubricant and means responsive to the temperature of said lubricant for controlling the operation of said heating element.

5. Absorption refrigerating apparatus including a part in which vapor is expelled from solution, a part in which such vapor is liquefied, a part in which the liquid is vaporized in the presence of an inert gas to produce a cooling effect, a part in which the vapor is absorbed from the inert gas, a power driven circulator connected to circulate fluids in the apparatus, said power driven means including a rotary drive member having its lower portion submerged in a lubricant, means for heating said part in which vapor is expelled, refrigeration demand responsive means for controlling the operation of said heating means and of said power driven means, means for controlling the viscosity of said lubricant, and means responsive to a condition of said lubricant which is a measure of the viscosity thereof for regulating said viscosity controlling means.

6. Absorption refrigerating apparatus including a part in which vapor is expelled from solution, a part in which such vapor is liquefied, a part in which the liquid is vaporized in the presence of an inert gas to produce a cooling effect, a part in which the vapor is absorbed from the inert gas, a power driven circulator connected to circulate fluids in the apparatus, said power driven means including a rotary drive member at least in part submerged in a lubricant, means for heating said part in which vapor is expelled, refrigeration demand responsive means for controlling the operation of said heating means and of said power driven means, means for controlling the viscosity of said lubricant, and means responsive to a condition of said lubricant which is a measure of the viscosity thereof for regulat-

ing said viscosity controlling means, said refrigeration demand responsive means being operative to render said viscosity responsive means operative or inoperative in accordance with refrigeration demand.

7. Sealed absorption refrigerating apparatus of the three-fluid type including an evaporator and an absorber connected for the circulation of inert gas therebetween, means for supplying refrigerant in liquid phase to the evaporator, a fan for circulating the inert gas between the evaporator and the absorber, a motor having a rotating element for driving said fan sealed within the apparatus and supported in a lubricant which serves to protect the said rotating element from contact with the active fluids within the apparatus, said lubricant being non-fluid at atmospheric temperatures whereby it is not displaced in handling of the apparatus, means for energizing said motor in response to refrigeration demand, means for rendering said lubricant fluid, and means for governing said means for rendering said lubricant fluid.

8. Sealed absorption refrigerating apparatus of the three-fluid type including an evaporator and an absorber connected for the circulation of inert gas therebetween, means for supplying refrigerant in liquid phase to the evaporator, a fan for circulating the inert gas between the evaporator and the absorber, a motor having a rotating element for driving said fan sealed within the apparatus, said rotating element being housed within a thin walled shell depending from said fan and sealed from the surrounding media, a field winding for said motor embracing the outside part of said shell, said shell being filled to a level sufficient to submerge said rotating element with a lubricant which is sufficiently thick at atmospheric temperatures to stall said motor, a heater for said lubricant also embracing said shell, means for energizing said refrigerant liquid supply means, said motor, and said heater, and means for de-energizing said heater only after energization thereof when said heater has rendered the lubricant fluid enough to allow said motor to start.

9. Sealed absorption refrigerating apparatus of the three-fluid type including an evaporator and an absorber connected for the circulation of inert gas therebetween, means for supplying refrigerant in liquid phase to the evaporator, a fan for circulating the inert gas between the evaporator and the absorber, a motor having a rotating element for driving said fan sealed within the apparatus, said rotating element being housed within a thin walled shell depending from said fan and sealed from the surrounding media, a field winding for said motor embracing the outside part of said shell, said shell being filled to a level sufficient to submerge said rotating element with a lubricant which is sufficiently thick at atmospheric temperatures to stall said motor, an electrical heater for said motor also embracing said shell, means for shielding said field winding from the effect of said heater, means for energizing said refrigerant liquid supply means, said motor and said electrical heater in response to refrigeration demand, a thermostatic switch connected to control said electrical heater and arranged to be responsive to the temperature of said lubricant for de-energizing said heater when said lubricant has been heated sufficiently to allow said motor to start, said heater being arranged to heat said lubricant sufficiently to al-

low said motor to start substantially at the time liquid refrigerant is supplied to said evaporator.

10. Absorption refrigerating apparatus including a generator for expelling refrigerant vapor from solution, an evaporator, means for liquefying refrigerant vapor produced in said generator and for supplying the liquid to said evaporator, an absorber connected with said evaporator for circulation of inert gas therebetween, a power driven circulator arranged to propel inert gas through said evaporator and said absorber, a motor for driving said circulator including a rotary part sealed within said apparatus, said rotating part being supported in a lubricant which is non-fluid at atmospheric temperatures, a heater for said lubricant, control means for said heater arranged to govern said heater to maintain said lubricant in a fluid condition, a heating means for said generator, and refrigeration demand responsive means for controlling the operation of said motor and said generator heating means, said generator heating means being constructed and arranged to maintain said generator continuously at a temperature such that the same is able to produce refrigerant vapor immediately said control mechanism responds to a demand for refrigeration.

11. Absorption refrigerating apparatus including a fluid circulator and a driving element therefor sealed within the apparatus, said driving element being positioned in a lubricant which is non-fluid at atmospheric temperatures, means for applying a driving force to said driving element and for applying heat to said lubricant at a first rate which is sufficient to render the lubricant fluid in a substantially fixed period of time and at a second lower rate which will maintain said lubricant in a fluid condition, refrigeration demand responsive means for energizing said means for applying a driving force to said driving element and for heating said lubricant, and means responsive to a change in the thermal condition of a portion of the apparatus induced by such energization for subsequently changing said heating rate.

12. Absorption refrigerating apparatus including a cooling unit, means for supplying a cooling medium to said cooling unit, a motor driven circulator heater assembly including a rotor sealed in said apparatus and immersed in a lubricant which is non-fluid at atmospheric temperatures, said motor-circulator heater assembly including means for heating said lubricant at a first rate to render the same fluid and at a second rate to maintain the lubricant fluid, means for simultaneously energizing said cooling medium supply means and said motor-circulator heater assembly to apply heat to said lubricant at said first rate, and means for changing the operation of said assembly to apply heat to said lubricant at said second rate when said lubricant has been rendered fluid.

13. Absorption refrigerating apparatus including a fluid circulator hermetically sealed therein, a driving device for said circulator also sealed with the apparatus, a lubricant sealed within said apparatus and contacting said driving device, said lubricant having a viscosity which is sufficiently high at atmospheric temperatures to prevent normal operation of said driving device, a heater for said lubricant, means for controlling the operation of said heater and arranged to render the same inoperative to heat said lubricant when the lubricant has been heated sufficiently

to lower its viscosity to a value such that it does not prevent operation of said driving device.

14. In an absorption refrigerating apparatus of the three fluid type including a generator, a liquefier, an absorber and an evaporator connected in circuit, a fluid circulator, a driving device for said fluid circulator, said fluid circulator and said driving device being hermetically sealed within said apparatus, a lubricant for said driving device hermetically sealed within said apparatus, said lubricant being sufficiently thick at atmospheric temperatures to stall said driving device, means for heating said lubricant, and means for rendering said lubricant heating means inoperative to heat said lubricant when said lubricant has been rendered sufficiently fluid to allow said driving device to operate.

15. In an absorption refrigerating apparatus of the three-fluid type including a generator, a liquefier, an absorber and an evaporator connected in circuit, a fluid circulator, a driving device for said fluid circulator, said fluid circulator and said driving device being hermetically sealed within said apparatus, a lubricant for said driving device hermetically sealed within said apparatus, said lubricant being sufficiently thick at atmospheric temperatures to stall said driving device, means for heating said lubricant, means for heating said generator, means for rendering said generator heating means and said lubricant heating means operative in response to refrigeration demand and for energizing said driving device, and means for rendering said lubricant heater inoperative to heat said lubricant when said lubricant has been rendered sufficiently fluid to allow said driving device to operate.

16. In an absorption refrigerating apparatus of the three-fluid type including a generator, a liquefier, an absorber and an evaporator connected in circuit, a fluid circulator, a driving device for said fluid circulator, said fluid circulator and said driving device being hermetically sealed within said apparatus, a lubricant for said driving device hermetically sealed within said apparatus, said lubricant being sufficiently thick at atmospheric temperatures to stall said driving device, means for heating said generator at a first rate which is sufficient to maintain the same at an operating temperature without the production of refrigerant vapor and at a second higher rate which will cause evolution of vapor in said generator, means for causing operation of said generator heating means at said second rate in response to a demand for refrigeration, and means for rendering said lubricant heater inoperative to heat said lubricant when said lubricant has been rendered sufficiently fluid to allow said driving device to operate.

17. In an absorption refrigerating apparatus of the three-fluid type including a generator, a liquefier, an absorber and an evaporator connected in circuit, a fluid circulator, a driving device for said fluid circulator, said fluid circulator and said driving device being hermetically sealed within said apparatus, means for imposing a stalling load upon said driving device, means for heating said generator, normally inoperative means arranged when operative to render said load imposing means inoperative to impose a stalling load upon said driving device after a time delay, control means arranged to render said generator heating means and said normally inoperative means operative in response to a de-

mand for refrigeration, and means for returning said normally inoperative means to inoperative condition after the expiration of said time delay.

18. An hermetically sealed absorption refrigerating apparatus including a boiler, a liquefier, an evaporator and an absorber connected in circuit, a fluid circulator hermetically sealed in said apparatus including a driving element which is contacted by a lubricant which is non-fluid at atmospheric temperatures, a heater for said boil-

er, means for heating said lubricant and for applying a driving force to said driving element, control means for governing the energization of said heater and of said last mentioned means, and means operative when said lubricant is rendered fluid to diminish the rate at which heat is applied to said lubricant to a value sufficient to maintain said lubricant in a fluid condition.

DONALD G. SMELLIE.
